CLAIM

The ornamental design for a child bath seat, as shown and described.

DESCRIPTION

FIG. 1 is a front perspective view of a child bath seat embodying the principles of the present invention; FIG. 2 is a rear perspective view of the child bath seat of FIG. 1;

FIG. 3 is a front view of the child bath seat of FIG. 1; FIG. 4 is a top view of the child bath seat of FIG. 1; FIG. 5 is a side view of child bath seat of FIG. 1 as viewed from the right hand side of FIG. 1, the opposite side being a mirror image thereof; and, FIG. 6 is a rear view of the child bath seat of FIG. 1. FIGS. 3 through 6 have been shown on an enlarged scale.
